(57) **CLAIM**

We claim the ornamental design for a needle protection for a syringe device, as shown and described.

DESCRIPTION

FIG. 1 is a perspective view at an angle from the front illustrating a needle protection for a syringe device.

FIG. 2 is a perspective view at an angle from the rear illustrating the needle protection for a syringe device.

FIG. 3 is a side view illustrating the needle protection for a syringe device.

FIG. 4 is a front view illustrating the needle protection for a syringe device; and,

FIG. 5 is a rear view illustrating the needle protection for a syringe device.

The broken lines represent portions of the article and form no part of the claimed design.
